CUTLERY HOLDER

Richard S. Latham, Chicago, Ill., assignor to Ekco Products Company, Chicago, Ill., a corporation of Delaware

Continuation of applications Ser. No. 53,747, Dec. 12, 1958, and Ser. No. 53,748, Dec. 12, 1958. This application Mar. 6, 1961, Ser. No. 64,316

Term of patent 14 years

(Cl. D44—29)

FIG. 1 is a top perspective view of a cutlery holder showing my new design, wherein the base includes an annular upstanding rim arranged in encircling relation to the lower portion of the neck of the holder.

FIG. 2 is an enlarged side elevational view thereof.

FIG. 3 is a top plan view thereof.

FIG. 4 is a bottom plan view thereof.

FIG. 5 is a top perspective view of another embodiment of my design wherein the lower portion of the neck is confined in a cavity defining a circular wall extending downwardly from the upper face of the base.

FIG. 6 is an enlarged side elevational view of the holder shown in FIG. 5.

FIG. 7 is a top plan view thereof.

FIG. 8 is a bottom plan view thereof.

The essential features of my design reside in the configuration of a cutlery holder having an elongated head portion presenting a pair of opposed upwardly converging flat faces which merge in an upwardly convexly curved upper end face of arcuate contour substantially conforming to the curvature of a cylinder having its axis parallel to said faces, a base of rectangular plan, said base and said head portion being connected by a neck portion rising centrally upwardly from said base, said neck portion having a pair of opposed parallel upright faces offset uniformly inwardly from the lower limits of said upwardly converging faces of the head portion, and occupying planes parallel to the axis of curvature of said upper end face of said head portion, as shown in full lines.

This application is a continuation of copending applications Serial Number D53,747 and Serial Number D53,748, filed December 12, 1958 both now abandoned.

I claim:

The ornamental design for a cutlery holder, as shown and described.
